THE INSTITUTE OF POLYGRAPHY, INC., WISCONSIN CITY, WISCONSIN

UNITED STATES PATENT OFFICE.

KENNETH RUSHTON, OF PHILADELPHIA, PENNSYLVANIA, ASSIGNOR TO THE BALDWIN LOCOMOTIVE WORKS, OF PHILADELPHIA, PENNSYLVANIA, A CORPORATION OF PENNSYLVANIA.

SWING-TRUCK FOR LOCOMOTIVES.

1,272,118.

Specification of Letters Patent.

Patented July 9, 1918.

Application filed March 6, 1918. Serial No. 220,696.

To all whom it may concern:

Be it known that I, KENNETH RUSHTON, a citizen of the United States, residing in Philadelphia, Pennsylvania, have invented 5 certain Improvements in Swing-Trucks for Locomotives, of which the following is a specification.

My invention relates to certain improvements in swing trucks, particularly those 10 adapted to be located under a locomotive.

The object of the invention is to design the truck so that it will readily accommodate itself to the lateral movement of the body of the locomotive when passing around 15 curves or on uneven tracks, and is particularly designed for narrow gage locomotives which are used on railways having sharp curves.

In the accompanying drawings:

20 Fig. 1 is a transverse sectional view on the line 1—1, Fig. 2; illustrating my improved swing truck.

Fig. 2 is a side view;

Fig. 3 is an inverted plan view of the 25 rocker;

Fig. 4 is a perspective view of the rocker bolt;

Fig. 5 is a front view illustrating a type 30 of truck in which the swing links are dispensed with;

Fig. 6 is a side view of the truck shown in Fig. 5;

Fig. 7 is a plan view of the same;

Fig. 8 is a transverse sectional view illustrating my invention as applied to a four 35 wheel truck;

Fig. 9 is a sectional view on the line 9—9, Fig. 8; and

Fig. 10 is a perspective view of the rocker 40 frame used in the construction illustrated in Figs. 8 and 9.

Referring in the first instance to Figs. 1 to 4 inclusive, which illustrate a swing truck in which swing links are used in ad-

45 dition to my improved rocker, 1 is a center pin which is pivoted to the frame of a locomotive, and on this pin are cast spring seats 2. 3 is the truck frame having bearings for the axle 4 on which are the wheels 5. This 50 type of truck has a single axle and two wheels.

10, 10 are the swing links made integral with the pivot pin 6 adapted to bearings 7 in the upper portion of the frame 3 and

held in the bearings by a clamp plate 8 and 55 bolts 9. The links 10 are connected at their lower ends by pins 11 to the arms 12 of the rocker frame 13. This rocker frame is U-shaped, as illustrated in Fig. 2, and one swing link is attached to one arm and the 60 other swing link is attached to the other arm, as shown clearly in said figures. The bearing surface 14 of this rocker frame is curved, as shown in Fig. 1, so that it will 65 rock against the under side of the center pin.

In order to yieldingly connect the rocker frame to the bearing, I mount within the center pin a coiled spring 15. A bolt 16 extends through this spring and through 70 an opening 17 in the bottom of the center pin 1 and has a T-head 18 curved on its upper side, as clearly shown in Fig. 4, and this curved head is adapted to a socket 19 on the under side of the rocker frame 13, as clearly 75 shown in Fig. 3. On the upper end of the bolt are two nuts 20 and located in the center pin 1 is a spring plate 21 forming an upper bearing for the spring 15. When the frame 13 swings on links 10 to the limit of 80 its capacity a strain, due to the curvature of the track, is then placed upon the bolt 16 and compresses the spring 15, which permits an additional lateral movement by reason of the frame 13 rocking on the curved surface 14 against the under side of the center 85 pin 1, which remains unyieldingly pivoted to the locomotive frame. The spring 15 also tends to return the frame to its normal position. 90

The truck illustrated in Figs. 1 and 2 is particularly adapted for use in connection with narrow gage locomotives, which are built to run on tracks having sharp curves, and while the ordinary swing of the body 95 of the locomotive is taken by the links 10 in the usual manner, when the locomotive passes around a sharp curve the body carrying the center pin 1 not only swings on the links of the rocker frame 13, but also 100 rocks on the bearing, so that the extended lateral movement of the frame of the locomotive can be accommodated by this construction.

In some instances, where the locomotive 105 is designed for the tracks of a railway in which the truck need not accommodate an extreme lateral movement, the swing links

may be dispensed with, as illustrated in Figs. 5, 6 and 7. In this instance, the rocker frame 13^a is connected by a pin 11^a directly to the truck frame 3^a, the frame 13^a 5 rocking on the bearing 1^a and accommodating itself to the lateral movement of the locomotive body.

While my invention is particularly adapted to the two wheel trucks shown in Figs. 1 to 7, inclusive, the invention can be applied to four wheeled trucks, such as that illustrated in Figs. 8 to 10, inclusive.

22 is the center bearing on which the body of the locomotive, or car, is mounted, and this center bearing is recessed at 23 on each side of the center and has an opening for the passage of two swing bolts 16^a, each provided at its upper end with a beveled head 18, which rests at the bottom of the recess 23. The opening in the center plate for the passage of the pin is sufficient to allow the pin to have a certain amount of lateral movement. On the lower end of the pin are nuts 20^a for carrying a spring 25 plate 21^a on which rests a spring 15^a. A spring block 24 is carried by the spring 15^a.

Each pin passes through a U-shaped frame 13^a, Fig. 10, beveled, or rounded, at each edge, and fits against the under side 30 of the center bearing 22. Each frame is preferably located in a recess formed by lugs or flanges 25. The arms 12^a of each rocker frame are connected by pivot pins 26 to the transverse bars 27, which form 35 the swing bolster. This bolster 27 is coupled to the frame of the car 28 by links 29, as shown in Figs. 8 and 9. By this construction, the truck frame can move laterally to a certain extent by merely swinging 40 on the links 29; but the moment the lateral movement is increased beyond the limit of the links, the bolster 27 will swing from the center bearing through the forked arms 13^a, which rock against the under side of 45 the center plate. The springs accommodate themselves to this movement and tend to return the parts to their normal position. In order to limit the movement of the rocker frame, I provide stops 30 on the swing bolster, as clearly shown in Fig. 8 by dotted lines.

By this improvement an extended lateral movement is obtained in a four or a six wheel truck.

55 In the construction illustrated in Figs. 1 to 7, inclusive, the center pin is a bearing carried by the locomotive and in Figs. 8 to 10, inclusive, the center plate 22 is the center bearing.

60 I claim:

1. The combination in a swing truck, of a center bearing carried by the locomotive or car body; a truck; a rocker frame pivoted to the truck and arranged to rock against the center bearing; and a spring carried by

the center bearing and tending to hold the frame against the bearing and to return the frame to its normal position.

2. The combination of a center bearing adapted to be secured to a locomotive, or 70 car body; a truck frame; a rocker frame; links connecting the rocker frame with the truck frame, said rocker frame resting against the under side of the center bearing; and a spring tending to draw the rocker 75 frame against the center bearing and to return the rocker frame to its central position.

3. The combination in a swing truck, of a 80 center pin; a truck frame having bearings for an axle; a rocker frame resting against the under side of the center pin; links connecting the rocker frame with the truck frame; a spring located in the center pin; and a bolt supported by said spring tending to normally retain the rocker frame in 85 the central position.

4. The combination of a center pin adapted to the frame of a locomotive, or car; a spring plate located in the bearing; a spring 90 between the plate and the bottom of the center pin; a rocker frame under the pin; a bolt extending through the spring plate and spring, through the center pin, and through the upper portion of the rocker frame and having a T-head provided with a round bearing surface adapted to a socket in the under side of the rocker frame; and a truck frame connected to the rocker frame.

5. The combination of a swing truck; a 100 center pin adapted to the frame of a locomotive, or car; a rocker having a curved upper surface bearing against the under side of the center pin; a spring and bolt connection between the rocker and the pin; 105 and a link connection between the rocker and the truck so that under certain conditions the lateral movement will be taken by the links and the extended lateral movement will be taken by the spring and rocker. 110

6. The combination in a swing truck for locomotives, of a center pin adapted to the frame of a locomotive; a truck frame; an axle mounted in bearings on the truck frame; links pivotally connected to the 115 upper portion of the truck frame; a U-shaped rocker frame having downwardly extending arms, the lower ends of the links being connected to the arms, one link being on each side of the truck frame, the upper 120 surface of the rocker frame being curved; a bolt extending through the rocker frame; and a spring tending to draw the bolt and the rocker frame against the center pin.

7. The combination in a single swing 125 truck for locomotives, of a center pin arranged to be pivoted to the frame of a locomotive, said pin being hollow; a truck frame; an axle having its bearings in the truck frame; a link located in each side of 130

the truck frame; a pivot pin mounted in the upper portion of the truck frame and through which the links are suspended; a U-shaped rocker frame having arms extending on each side of the truck frame beyond the links, said links being pivotally connected to the lower portion of the rocker frame, the upper portion of the rocker frame being curved so as to allow the rocker and truck to swing laterally in respect to the longitudinal line of the locomotive; a T-headed bolt having its bearings in the rocker frame and extending through the frame and through the hollow center pin; a coiled spring located in the center pin; a spring plate mounted above the spring, the bolt extending through the spring and the spring plate; and nuts on the bolt, the spring tending to hold the rocker against the bearing and to return the rocker to its normal position.

In witness whereof I affix my signature.

KENNETH RUSHTON.
